UNITED STATES PATENT OFFICE

WILLIAM A. DOBSON, OF BRIDGEPORT, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed February 14, 1929. Serial No. 339,764.

This invention relates to carriage-escape-
ment mechanism for typewriting machines,
and applies more particularly to typewriters
of the portable type, wherein extreme light-
ness, compactness, accessibility, cheapness
and durability are of prime importance.

One feature of this invention is the provi-
sion of an escapement mechanism which is
efficient in its operations and readily installed
in the machine.

Another feature is the provision for the
working parts of the mechanism of a novel
system of ball-bearings to minimize the fric-
tion of the spring-propelled carriage, and in-
creasing ease and speed of operation.

Another feature lies in the simplicity of
the parts, permitting lightness of weight
without sacrificing dependability of opera-
tion.

Another feature is the use of a compara-
tively large ball-bearing to withstand the
strains set up in the moving parts especially
during the intermittent motion of letter-
spacing, in combination with a small and
compact ball-bearing, the two co-operating to
support the shaft.

Another feature is the employment of the
escapement-wheel to form part of a ball-race
for the large ball-bearing. This cheapens
the construction of the parts and facilitates
their assembly.

Provision is made for substantially noise-
less return of the carriage, the escapement-
wheel not rotating during this operation.

In this invention the letter-spacing escape-
ment-mechanism may be assembled complete
and mounted as a unit in the machine. This
unit includes a shaft and an improved ar-
rangement of bearing supports therefor,
along with other features. The movement
of the escapement-wheel, which is mounted on
the shaft, is controlled through the reciproc-
ating motion of a holding dog and a feeding
dog, the details of which are fully disclosed
in my Patent No. 1,696,906 of January 1, 1929.

The shaft is provided with a pinion, free to
rotate on the shaft, independent of the es-
capement-wheel in one direction during the
carriage-return movement, but is prevented
from moving, independently of the escape-

ment-wheel, in the opposite direction during
letter-spacing by reason of a pawl mounted
on the escapement-wheel and engaging the
teeth of the pinion. During the letter-spac-
ing operation of the mechanism, therefore, 55
the pinion and the escapement-wheel rotate
together, whereas on the carriage-return
movement of the machine, the pinion rotates
independently of the escapement-wheel and
the escapement-wheel remains stationary. 60
The pinion is in continuous engagement with
the rack which is secured to the carriage of
the machine.

In order to rotatably support the shaft and
compact the mechanism, a pair of ball-bear-
ings are employed, one bearing being sub-
stantially larger than the other. This dif-
ference in size of the ball-bearings enables
the size of the mechanism to be materially re-
duced while providing for rigidity. The 70
small ball-bearing is mounted on the rear end
of the shaft, while the large ball-bearing is
mounted immediately in front thereof, and
towards the center of the shaft. In order
to form a seat for the large ball-bearing, the 75
shaft is provided with a flange, upon the per-
iphery of which the large balls can rotate,
and to simplify the construction of the ball-
race the escapement-wheel is mounted direct-
ly against the side of this flange forming 80
therewith part of the race for the balls.

Upon that portion of the shaft extending
beyond the escapement-wheel is mounted the
rack-engaging pinion, retained on the shaft
by a large-headed screw, inserted longitudi-
nally in the end of the shaft, the head of the
screw extending beyond the periphery of the
shaft forming a shoulder for this purpose.
The opposite end of the shaft has two nuts 85
mounted thereon. The inner nut is faced to
form in part a race for the small ball-bear-
ing and provides means of adjustment for
both bearings. The second nut locks the
faced nut to prevent turning after the ball- 90
bearings have been adjusted thereby.

It will be noted that the escapement-wheel
and the faced nut are thrust-bearings for
the longitudinal strains that are set up dur-
ing the operation of the machine. 100

Other features and advantages will herein-after appear.

In the accompanying drawing:

Figure 1 is a perspective view of parts of 5 a typewriter, showing this invention incorporated therein.

Figure 2 is a detail perspective view, having portions broken away to show the inner structure of the parts.

10 Figure 3 is a vertical sectional view, showing the parts in their operative relation to each other.

Referring to the drawing, 10 is a typewriting machine frame having two carriage-tracks 11 (one not shown). Balls 12 travel on said tracks and support a carriage 13 movable on the track. The carriage 13 has a platen 14 rotatably mounted therein, and against which the usual type-heads (not shown) can strike. The carriage 13 has secured thereto a rack 15. The frame 10 supports a spring-drum 16, which is connected by a tape 17 to the carriage for drawing the latter in letter-feeding direction from right 25 to left in the machine.

The frame 10 has secured thereto a plate 18 upon which the escapement-mechanism is assembled as a unit. This plate supports a holding dog 21 and a feeding dog 20 mounted 30 in a member (not shown) and which may be pivoted at 50 to lugs 51, as more fully described in the above-mentioned patent. The plate 18 is offset at 22 and has a centrally-located hole 23 therein. In this hole a hub 24 of a ball-race 25 is tightly fitted with its flange 26 abutting said plate 18. This race 25 has a raceway 27 which is shown herein as conical. On the hub 24 a second ball-race 28 is mounted with its flange 29 against said 35 plate 18. The ball-race 28 has a beveled internal shoulder 30, against which the end of the hub 24 is riveted over to force together the plate 18 and the two ball-races 25 and 28. The ball-race 28 has a raceway 31 which may 40 also be conical, as shown.

A shaft 32 has an integral flange 48 having an annular seat or shoulder 33 and a ball-race 34. An escapement-wheel 35 is assembled immovably on the seat 33 and abuts the 45 side of said ball-race 34. A pinion 36 is rotatably mounted on the shaft 32 and is held thereon by the head of a screw 37, which is screwed into the end of the shaft, the head of the screw 37 having a larger diameter than the shaft 32 to retain the pinion 36 on the shaft 32. The pinion has a hub 38 to reduce end friction that might be caused by the pinion-teeth 39.

When the escapement-wheel 35 and pinion 50 36 have been assembled on the shaft 32, the latter is passed through the hub 24 until the escapement-wheel 35 rests against balls 40. A faced cap 41 is then screwed on the shaft 32 for adjustment with balls 42, and is retained in adjustable position by a lock-nut 55

43. This assembling of the parts holds the escapement-wheel 35 and pinion 36 in fixed rotative relation with the plate 18 and therefore with the machine.

In order to prevent independent counter-clockwise rotation of the pinion during letter-space actuation of the escapement-wheel 35, the latter has a stud 44 in which is set one end of a curved leaf-spring 45. The latter presses against a pawl 46 pivotally supported 70 on a stud 49 on said wheel, and which pawl 46 engages the teeth 39 of the pinion 36 to hold said wheel 35 and pinion 36 in fixed relation during letter-spacing operation. When the carriage 13 is returned to the right for typing a new line, the rack 15 is also carried to the right, thereby rotating the pinion 36 clockwise. The pawl 46 does not transmit this motion to the escapement-wheel 35, so that during this operation the escapement-wheel 35 and the dogs 20 and 21 are stationary. Considerable noise is prevented by this arrangement. In order to provide the escapement-wheel 35 and parts with a positive lock against moving during the carriage-return operation, a pawl 19, pivoted to the plate 18, engages the teeth of the escapement-wheel 35 when urged to rotate clockwise.

In order to provide space for the shaft 32, 95 cap 41 and lock-nut 43, a hole 47 is made in the frame 10, as shown in Figure 3.

It will be understood, of course, that various modifications might be made in the shape of the ball-races 25 and 28, or, in other details, without departing in any way from the scope of this invention.

The bracket 18, forming the main member of the escapement-unit, corresponds with the bracket 67 of said Patent 1,696,906, (said bracket 67 having ears 66 corresponding with ears 51 having pivot bearings 50 at Figure 1 of this case). This bracket is screwed to the shift-frame 10 of an Underwood portable typewriting machine.

Variations may be resorted to within the scope of the invention, and portions of the improvements may be used without others.

Having thus described my invention, I claim:

1. In a carriage-feeding device for typewriting machines, the combination with a carriage and means for moving the same, of a letter-spacing mechanism including a shaft 115 rotated in one direction by the carriage, an escapement-wheel and flange on the shaft, a pair of ball-bearings of different diameters for the shaft, the smaller one bearing directly against the shaft, the larger one opposed to the smaller and bearing against the periphery of said flange, the side of the escapement-wheel bearing against the large ball-bearing and taking the endwise thrust of the shaft in one direction, a carriage-rack, a pinion loose on said shaft and wholly sup- 120 125 130

ported thereby, and connected by a pawl to said escapement-wheel, and an intermitting device controlling the mechanism for giving the carriage a step-by-step movement.

5 2. In a carriage-feeding device for typewriting machines, the combination with a carriage and means for moving the same, of a letter-spacing mechanism, including a shaft, effective to be rotated in one direction by the carriage, a flange on the shaft, a pair of ball-bearings wholly supporting the shaft, one bearing acting directly against the shaft, the other acting against the periphery of said flange, an escapement-wheel on said shaft at the side of said flange, a pinion wholly supported on the shaft to be geared to said carriage and free to rotate on said shaft independently of the escapement-wheel during the carriage-return movement, a pawl 10 connecting said pinion to said wheel, means coacting with said wheel for giving the carriage a step-by-step movement during the typing operation, a bracket placed between said ball-bearings and fixed directly thereto, and means upon the end of the shaft for tightening both ball-bearings.

3. A letter-spacing device for typewriting machine carriages including a support for the device, having an opening therein, a rotatable shaft actuated by said carriage, means coacting with the shaft for giving the carriage an intermittent feed, and a pair of ball-bearings for the shaft including a pair of annular ball-race-disks, one for each bearing, one disk having a hub, effective to pass through the opening in the support and the central opening in the other disk, and secure said support between the disks for holding the device in the machine.

4. In an escapement-unit for attachment to a typewriting machine, the combination of a main bracket, an annular ball-cup fitted against one side of said bracket and having a hub-portion fitted in a perforation in said bracket, a second annular ball-cup upon the other side of said bracket and fitted upon said hub, means forcing said cups against the opposite faces of said bracket, a shaft extending through the cups and bearing an escapement-wheel, a row of balls in the first cup and running upon said shaft, a second row of balls confined by the second cup and bearing against said escapement-wheel, and a cap threaded upon said shaft and pressing against the first row of balls to tighten both ball-bearings.

5. In an escapement-unit for attachment to a typewriting machine, the combination of a main bracket, an annular ball-cup fitted against one side of said bracket and having a hub-portion fitted in a perforation in said bracket, a second annular ball-cup upon the other side of said bracket and fitted upon said hub, means forcing said cups against the opposite faces of said bracket, a shaft extend-

ing through the cups and bearing an escapement-wheel, a row of balls in the first cup and running upon said shaft, a second row of balls confined by the second cup and bearing against said escapement-wheel, a cap threaded upon said shaft and pressing against the first row of balls to tighten both ball-bearings, a pinion mounted upon said shaft on the opposite side of the escapement-wheel from said bracket, and a pawl between the escapement-wheel and the pinion.

6. In a carriage-escapement unit for attachment to a typewriting machine, the combination with a bracket, of two circular sets of bearing balls, an annular cup upon one side of said bracket for one set of balls, an annular cup upon the other side of said bracket for the other set of balls, means securing said bracket and cups together, one of said cups forming a rivet which rivets both cups to the sides of said bracket, a shaft extending through said annular cups and through said bracket, an escapement-wheel upon said shaft and one side of said escapement-wheel bearing against the balls in one set, to take the endwise thrust of the shaft in one direction, and means adjustable upon the end of the shaft for pressing the other set of balls into its cup and against said shaft, thereby tightening both sets of balls.

7. In a carriage-escapement unit for attachment to a typewriting machine, the combination with a bracket, of two circular sets of bearing balls, an annular cup upon one side of said bracket for one set of balls, an annular cup upon the other side of said bracket for the other set of balls, means securing said bracket and cups together, a shaft extending through said annular cups, an escapement-wheel upon said shaft and bearing against the balls in one set, and means adjustable upon the end of the shaft for pressing the other set of balls into its cup and against said shaft, thereby tightening both sets of balls, one of said cups having a hub extending through the other cup and holding the latter against said bracket.

8. In a carriage-escapement unit for attachment to a typewriting machine, the combination with a bracket, of two circular sets of bearing balls, an annular cup upon one side of said bracket for one set of balls, an annular cup upon the other side of said bracket for the other set of balls, means securing said bracket and cups together, one of said cups forming a rivet which rivets both cups to the sides of said bracket, a shaft extending through said annular cups and through said bracket, an escapement-wheel upon said shaft and one side of said escapement-wheel bearing against the balls in one set, to take the endwise thrust of the shaft in one direction, means adjustable upon the end of the shaft for pressing the other set of balls into its cup and against said shaft, thereby tight-

ening both sets of balls, a pinion upon the other side of said escapement-wheel for engagement with a carriage-rack, and a driving pawl between said pinion and said escapement-wheel.

9. In a carriage-escapement unit for attachment to a typewriting machine, the combination with a bracket, of two circular sets of bearing balls, an annular cup upon one side of said bracket for one set of balls, an annular cup upon the other side of said bracket for the other set of balls, means securing said bracket and cups together, one of said cups forming a rivet which rivets a

shaft extending through said annular cups and through said bracket, an escapement-wheel upon said shaft and one side of said escapement-wheel bearing against the balls in one set, to take the endwise thrust of the shaft in one direction, a cap threaded upon the end of said shaft to tighten both sets of balls, and a framework-member to which said bracket is attached, said framework-member having an opening through which said shaft extends, said cap being at one side and said cups being at the other side of said framework-member.
